CLOTHES WRINGER ATTACHMENT

Harry Condor Ransley, Appleton, Wis.

Application August 1, 1934, Serial No. 737,977

2 Claims. (Cl. 68—32)

This invention appertains to new and useful improvements in washing machines and more particularly to an attachment for wringers whereby clothes will be prevented from winding around the rolls in the operation of being wrung.

The principal object of the present invention is to provide an attachment for washing machine wringers which can be readily applied to conventional wringers without altering the construction thereof.

Another important object of the present invention is to provide a wringer attachment for preventing the winding of clothes on the wringer rolls which in construction is simple and such as to permit the manufacture thereof at a very low cost.

These and numerous other important objects and advantages of the invention will become apparent to the reader of the following specification.

In the drawing:

Figure 1 is a vertical sectional view through a conventional wringer mount showing the present invention in side elevation.

Figure 2 is a vertical sectional view taken substantially on line 2—2 of Figure 1.

Figure 3 is a fragmentary perspective view of the attachment separated from the wringer.

Referring to the drawing wherein like numerals designate like parts, it can be seen that, in Figure 1, numeral 5 represents the usual pressure roll while numeral 6 represents the drive or power roll, the same having the shank extension 7 for connection at 8 with the usual drive means (not shown).

Numerical 9 represents a frame for the wringer which is provided with a bridge portion 10 through which the feed screw 11 is adjustable to regulate the tension of the spring 12 for the pressure roll.

5. This spring 12 is elongated as shown in Figure 1 and bears against the bearing blocks 13—13 for the pintle ends of the roll 5.

In carrying out the present invention, it is the intention to provide stops on the rolls whereby clothes will be prevented from winding on the rolls to the end that damage to the rolls and injury to the fingers of the operator will be entirely eliminated.

In Figure 3 numeral 14 generally refers to the upper stop, while numeral 15 generally refers to the lower stop. The upper stop is of the same construction as that shown for the lower stop, each consisting of a dovetail shaped rib merging with inclined top walls 17—17 terminating at their longitudinal edges in depending parallel side walls 18—18. The difference between the stop 14 and the stop 15 is that the stop 15 is provided with

openings 19 in the opposite walls of the dovetail shaped rib 16 at the opposite ends thereof for receiving the lower terminals a—a of the straps 20. These straps extend over the rib 16 of the stop 14 and arch outwardly and extend downwardly to have their terminals disposed into and bent backwardly through the openings 19 in the rib 16 of the lower stop 15.

To retain the upper stop 14 in place, a slide for each end thereof is provided. This slide consists of an elongated plate 21 having downwardly converging flanges 22—23 which are capable of snugly hugging the side walls of the rib 16. These flanges 22—22 are located adjacent one end of the plate 21 at which end an extension is provided which is bent upwardly and downwardly to provide a handle 23.

It will be observed that, with the flanges 22—22 engaging the rib 16 of the upper stop 14, these sliding retainers can be slid so that the plates 21 are engaged between the ends of the spring 12 and the corresponding bearing blocks 13 as shown in Figure 1. Thus the upper stop 14 is retained in place and with the use of the bands 20 the lower stop 15 is firmly retained against the lower or power roll 6. Thus clothes will be prevented from winding around the rolls as they will be deflected by the stops 14 and 15.

The stops 14 and 15 serve effectively to prevent clothes from winding around the rolls and it is further understood that this construction can be modified in various respects to adapt the same to various other types of washing machine wringers.

While the foregoing specification sets forth the invention in specific terms, it is to be understood that numerous changes in the shape, size, and materials may be resorted to without departing from the spirit and scope of the invention as claimed hereinafter.

What is claimed is:

1. In combination, a wringer provided with a pair of coaxing rolls, a blade for engaging each of the rolls to prevent clothes from winding thereon, and spring strap members connecting the upper blade with the lower blade to hold the same against the rolls.

2. In a wringer having a pair of rolls, one of the rolls, being journaled in slidable bearing blocks, and having spring means pressing against the bearing blocks to force the rolls together, a stripper blade having its edge resting on one of the rolls and members slidably connected to the stripper blade and projecting between the spring means and the bearing blocks to hold the stripper blade in place.
